(57) **CLAIM**

The ornamental design for an mug wrap, as shown and described.

DESCRIPTION

FIG. 1 is a side perspective view of an mug wrap in accordance with the present invention in the open position; FIG. 2 illustrates a side perspective view of the mug wrap in an alternative intermediate position.

FIG. 3 is a top plan view of the mug wrap with the mug wrap in the open position.

FIG. 4 illustrates a top plan view of the mug wrap in the intermediate position.

FIG. 5 is a top plan view of the mug wrap in an alternative closed position.

FIG. 6 is a front elevation of the mug wrap in the intermediate position.

FIG. 7 is a right side elevation of the mug wrap in the intermediate position.

FIG. 8 is a rear elevation of the mug wrap in the intermediate position; and,

FIG. 9 is a left elevation of the mug wrap in the intermediate position.

The broken lines in FIGS. 1-9 depict environmental structures that form no part of the claimed design.
